APPARATUS FOR DISPENSING BEER

Ray Knapp, Rochester, N. Y.

Application June 27, 1934, Serial No. 732,691

2 Claims. (Cl. 225—1)

My invention relates to a method and apparatus for dispensing beer, and has for its principal object to afford a structure that employs a cooling chamber made of glass or glass lined material, the beer being retained in the glass cooling chamber and conducted therefrom directly to the dispensing faucet.

The glass or glass lined cooling chamber referred to is mounted in a refrigerating cabinet of suitable construction, and it is a further object of the invention to eliminate the use of the block tin coils commonly employed in the dispensing and cooling of beer by substituting for such block tin coil a glass chamber, and thus obviate the recognized objections to drawing beer from a tin coil.

In order to secure the necessary cooling surface for the beer, the glass chamber must be of considerable volume and cross-section, and it is a further purpose of the invention to control and feed the beer in such a way that the contents of the glass cooling chamber do not have to be wasted at any time, but are always in satisfactory condition and available for use.

In using the conventional type of cooler with block tin coils, after beer lies in the coil overnight or for a considerable length of time, it acquires an unpleasant taste and is not in fit condition for consumption, so that the beer within the coil must be drawn off and thrown away, also when a fresh barrel of beer is put on the line, air is pocketed in the coil, causing the beer that is first drawn off to be exceedingly frothy, and this must consequently be thrown away after blowing out the line, and it is a further purpose of the invention to eliminate these disadvantages and effect substantial economies by the use of a cooling chamber of glass, or glass lined, that is always filled and connected with a full barrel, so that no opportunity is afforded for air to pocket in the cooling chamber or in the pipe leading thereto and a supply of satisfactory beer is constantly on tap.

A further object of the invention is to provide a system and apparatus whereby a plurality, or as many barrels as desirable may be connected together in series, the barrel at one end of the series communicating with the pressure line and the barrel at the other end of the series with the cooling chamber, thus making it possible to take out the empty barrel and insert a fresh one at any time, without disturbing the beer in the cooling chamber, and without wasting any beer.

Another object of the invention is to provide simple and practical mechanism for conveniently

supporting a series of glass cooling chambers within a refrigerating cabinet in such a manner as to permit their ready removal, and connecting them with the supply barrels by means of pipes arranged in such a way that the conducting tubes to the various barrels can be readily cleaned at frequent intervals without disturbing the contents of the glass cooling chambers, so that the rubber conducting tubes may be more frequently cleaned than is necessary in the case of the glass cooling chambers, this cleaning of the rubber tubes being permissible without wasting the contents of the glass cooling chambers or otherwise interfering with the operation of the system.

To these and other ends, the invention consists in the method and apparatus that will appear from the following description, when read in conjunction with the accompanying drawings, the novel features being pointed out in the claims following the specification.

In the drawings:

Fig. 1 is a general view illustrating a refrigerating cabinet in section, a series of glass cooling chambers therein, and the arrangement of barrels connected with the respective cooling chambers;

Fig. 2 is a transverse vertical sectional view through the refrigerating cabinet, illustrating one of the glass cooling chambers and the connections between it and the dispensing faucet, also the pipe which leads to the barrel;

Fig. 3 is a sectional view on line 3—3 of Fig. 2;

Fig. 4 is a sectional view on line 4—4 of Fig. 2, and

Fig. 5 is an enlarged detail sectional view of one of the barrel fittings.

Referring more particularly to the drawings, in which like reference numerals refer to the same parts throughout the several views, 1 designates each of a series of glass cooling chambers having a curved top portion 2 terminating in a vertical neck 3 and a horizontal outlet 4 which may be connected through a rubber tube 5 with a pipe leading to the dispensing faucet 6. While I have referred to the cooling chamber in the specification and claims as of glass, it is to be understood that this is intended to comprehend any glass lined or porcelain lined material as well.

The cooling chamber 1 is also provided with a curved bottom portion 7 and a depending inlet portion 8 which is suitably connected with a pipe 9 from the bottom of which a rubber tube 10 leads to the barrel in the cellar or place of storage.

The cooling chamber 1 is located in a refrigerating compartment 11 containing water or other refrigerating medium which is kept cooled by the refrigerating unit 12, the compartment 11 being 5 watertight and preferably provided with a glass panel or front wall 13 through which the cooling chambers 11 can be seen. 14 is a removable cover permitting access to the cooling chambers.

The rubber tube 10 connects with the upper 10 end 15 of the outlet tube of a barrel, the same forming part of a fitting that is removably positionable on each barrel when the same is ready for use. Each fitting, which is shown in detail in Fig. 5, comprises an inlet 16 adapted to receive 15 a connection 17 permanently attached to the rubber tube 18 which leads to the pressure line 19 containing a supply of carbonic acid gas. The connection 17, which is removably attached to the inlet 16, carries a rubber check valve 20, and 20 21 is a second rubber check valve secured at the other end of the inlet 16. 22 is an inlet pipe located between the inlet 16 and the outlet tube 15, and provided with a cut-off plug valve 23, said pipe 22 affording means for connecting one barrel 25 with the outlet tube of a second barrel, as shown in Fig. 1.

With this arrangement, two or more barrels can be used in series, as shown in Fig. 1, the first 30 barrel A being connected by the rubber tube 18 with the pressure line, its outlet tube 15 being connected by a rubber tube 24 with the inlet 22 of the second barrel A', the outlet tube of barrel A' being similarly connected with the inlet 22 of barrel A², and the outlet tube of the last barrel 35 A² being connected through the rubber tube 10 and pipe 9 with its glass cooling chamber.

The pressure line is not connected with barrels A' or A², but only with barrel A, the latter being charged and through its connection with barrels 40 A' and A², maintaining a sufficient pressure thereon. When barrel A is empty, it is removed after first closing the pressure line valve 25 and also valve 26 which controls the inlet into barrel 45 A'. The rubber tube 18 is disconnected from barrel A, and likewise the tube 24, and barrel A is removed.

If the contents of barrel A' are partially drawn off, it is preferable to connect barrel A' with the pressure line and insert the fresh barrel between 50 barrels A' and A². To do this, it is necessary first to close the valve 27 controlling the outlet tube of barrel A', and valve 23 controlling the inlet to barrel A², then connect barrel A' with the pressure line tube 18 and with the fresh barrel 55 that is inserted between barrels A' and A² in the same manner and relation that barrel A' occupies in Fig. 1 between barrels A and A². The valve 25 can then be opened, the valves of the several barrel outlet tubes can be opened, and 60 beer is again ready for dispensing. During this operation of inserting a fresh barrel, the proper valves 33 are also closed.

With this procedure, beer is always drawn from a full barrel, and there is no chance for air to 65 pocket in the pipe leading to the cooling chamber or in the cooling chamber, and likewise no necessity for blowing out the pipe or wasting any beer, as is generally done in connection with the block tin coil installation where a single barrel is 70 connected at a time. With applicant's arrangement, since glass has no deteriorating or displeasing effect on the beer, the contents of the glass cooling chamber are fresh and palatable after standing in the glass for a number of hours, 75 and can be drawn off and consumed as though

drawn directly from a barrel. The desired effect can be had by using only two barrels in series instead of three, although it is more convenient and practical to use three or more.

In order to provide for readily cleaning the 5 rubber tubes connecting the barrels with the respective pipes 9, I employ a universal transverse pipe 31, see Fig. 1, which is connected with each of the pipes 9 and is provided with valves 32 at its ends and also between each of the pipes 9, 10 while the latter are provided with valves 33 above and below the transverse pipe 31. With this disposition of the pipe 31 and controlling valves, beer may be conveyed from any barrel or group of barrels to any selected cooling chamber, and the rubber tubes connecting with the barrels can be cleaned at frequent intervals by closing all valves 33 located above the transverse pipe 31, leaving open the lower valves 33, and then by suitably connecting together the ends of the rubber tubes, a complete circuit through them can be completed as well as the pipe 31 and connections leading thereto. After the rubber tubes are thus cleaned, they are again connected to the barrels and the upper valves 33 opened to permit 20 a supply of beer to be fed to the cooling chambers.

The glass cooling chambers are removably supported in the refrigerating cabinet in a convenient and practical way, and to accomplish this I preferably employ a support comprising a plate 41 30 mounted on removable legs 42 that rest on the bottom of the cabinet 11. The plate 41 has a central opening surrounded by a seat to receive the curved bottom portion 7 of the glass cooling chamber, which latter rests upon rubber or resilient supporting pads 43 held in suitable grooves 44 in the seat of the plate 41. 45 designate retaining rods having hooks 46 at their lower ends engaging eyes which are anchored in the bottom wall of the cabinet 11, said rods 45 when in vertical position being located in the slots 47 of the bottom plate 41 and adapted to be swung laterally away from said slots 47 to permit removal of the cooling chamber.

The upper threaded ends of the rods 45 extend 45 through openings in a top plate 48 and are held in engagement therewith by the wing nuts 49, see Fig. 1. The top plate 48 has a central opening surrounding the neck 3 and is provided with suitable grooves that receive the rubber pads 50 50 that engage and rest upon the top portion 2 of the glass cooling chamber, said plate being held in sufficiently tight engagement with the top portion of the cooling chamber, and the cooling chamber being held in its proper position by tightening the nuts 49 on the upper ends of the rod 45 against the top of the plate 48, as shown in Fig. 1. To remove the cooling chamber for any reason, the nuts 49 are loosened and taken off, the plate 48 lifted off the rods over the neck 3 and outlet 4, it being understood that the tube 5 is first removed, then the rods 45 are swung laterally out of engagement with the supporting plate 41, and the cooling chamber can then be removed if necessary for replacement or any other 65 required purpose.

While the invention has been described with reference to certain structure and procedure, it is not confined to the details herein recited, and this application is intended to cover any modifications or departures coming within the purposes of the invention or the scope of the following 70 claims.

I claim:

1. Apparatus for dispensing beer comprising a 75

- glass cooling chamber having rounded top and bottom portions terminating in an outlet and inlet respectively, a support having a central opening and a seat cooperating with the rounded part of said bottom portion, resilient pads in said rounded part of the seat engaging said bottom portion, a retaining plate engaging the rounded part of said top portion of the cooling chamber and having a central opening to receive the outlet, resilient pads around said opening located between the retaining plate and the rounded part of said top portion, retaining rods removably engaging guideways in the support, and means for securing said rods in relation to said retaining plate so as to retain the latter and the cooling chamber in position.
2. Apparatus for dispensing beer comprising a glass cooling chamber having rounded top and bottom portions terminating in an outlet and inlet respectively, a support having a seat engaging the outer surface of the rounded part of said bottom portion, a retaining plate engaging the outer surface of the rounded part of said top portion, said support having lateral slots or recesses, retaining rods attachable at their lower ends and removably positionable in said slots in the support, the upper ends of said rods extending through openings in said retaining plate, and means for fastening said rods in relation to said retaining plate to hold the latter in fixed engagement with the cooling chamber.

RAY KNAPP.
